UNITED STATES PATENT OFFICE.

FRANCIS A. GOODROW, OF ELGIN, ILLINOIS, ASSIGNOR TO ELGIN NATIONAL WATCH COMPANY, OF ELGIN, ILLINOIS, A CORPORATION OF ILLINOIS.

DESIGN FOR THE HANDS OF A TIMEPIECE.

55,785.

Specification for Design.

Patented July 13, 1920.

Application filed November 6, 1919. Serial No. 336,183. Term of patent 14 years.

To all whom it may concern:

Be it known that I, FRANCIS A. GOODROW, a citizen of the United States, residing at Elgin, in the county of Kane, State of Illinois, have invented a new, original, and ornamental Design for the Hands of a Timepiece, of which the following is a description, reference being had to the accompanying drawing, forming part thereof.

The figure is a plan view showing the hands of a timepiece embodying my design.

I claim:

The ornamental design for the hands of a timepiece, as shown.

In testimony whereof I affix my signature.

FRANCIS A. GOODROW.
